US00D983555S

(12) **United States Design Patent** (10) **Patent No.:** **US D983,555 S**
(45) **Date of Patent:** **** Apr. 18, 2023**

(54) **WRAP DISPENSER WITH RIBBED CORE**

- (71) Applicant: **Pratt Corrugated Holdings, Inc.**,
Brookhaven, GA (US)
- (72) Inventors: **Hannah Conrad**, Memphis, TN (US);
Corey Crane, Atlanta, GA (US); **Travis
Walters**, Atlanta, GA (US)
- (73) Assignee: **Pratt Corrugated Holdings, Inc.**,
Brookhaven, GA (US)

(**) Term: **15 Years**

(21) Appl. No.: **29/713,475**

(22) Filed: **Nov. 15, 2019**

(51) **LOC (14) Cl.** **20-02**

(52) **U.S. Cl.**
USPC **D6/518**

(58) **Field of Classification Search**

(57) **CLAIM**

The ornamental design for a wrap dispenser with ribbed core, as shown and described.

DESCRIPTION

FIG. 1 is a top perspective view of the claimed design showing the claimed dispenser.

FIG. 2 is a bottom perspective view thereof showing the claimed dispenser.

FIG. 3 is a front elevation view thereof, which is identical to a rear elevation view thereof.

FIG. 4 is a right-side elevation view thereof, which is identical to a left-side elevation view thereof.

FIG. 5 is a sectional view thereof, taken along line 5-5 in FIG. 4.

FIG. 6 is a top plan view thereof; and,

FIG. 7 is a bottom plan view thereof.

The broken lines showing in the figures is included for the purpose of illustrating portions of the wrap dispenser with ribbed core and form no part of the claimed design.

1 Claim, 5 Drawing Sheets
